UNITED STATES PATENT OFFICE

WALTER SCHAFFER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

CIRCUIT ARRANGEMENT FOR TELEPHONE OR SIGNALING SYSTEMS WITH TUBE SENDERS

Application filed March 22, 1923, Serial No. 626,736, and in Germany April 13, 1922.

The present invention relates to a circuit arrangement which may be used for transmitting signals or radiating speech by means of tube senders. The circuit arrangement is 5 represented in the drawing.

The current source is connected to the terminals 1 and 2. The current is supplied through the choke coil 3 to the oscillating tube 4 the anode of which is in turn connected 10 through the condenser 5 with the oscillating circuit 6. Current is supplied in the usual manner to the cathode through an input circuit, and the grid is connected to the circuit 6 through the grid condenser 8. The cathode 15 of the oscillating tube 4 is connected with a condenser 9 which in turn is connected with the grid conductor through a choke coil 10 adapted to prevent the passage of high frequency currents. The condenser 9 is connected 20 in parallel with the modulating tube 11 the grid of which is controlled through the transformer 12 by means of a telephone transmitter 13 which is connected in series with the talking current supply 14. If the 25 grid of the modulating tube 11 is affected by a negative momentary potential, then the tube resistance will be infinitely high, the grid of the oscillating tube 4 cannot discharge and the oscillating current in the circuit 6 must become zero. If the grid of the 30 modulating tube 11 is affected by a positive momentary potential, then its resistance will become very small, the grid of the oscillating tube 4 will be discharged and the current in the 35 oscillation circuit 6 will be raised to its highest value. This arrangement is of particular advantage because the anode of the modulating tube 11 is connected directly with the cathode of the oscillating tube 4 40 whereby the latter may be readily grounded. The heated cathode of the modulating tube 11 is protected from high frequency currents by means of the choke coil 10, and the condenser 9 provides a further protection 45 against high frequency currents for the tube 11. When a negative potential is applied to the grid of the modulating tube 11, and its resistance is therefore infinitely high then, as above stated, the grid of the oscillating 50 tube 4 cannot be discharged and the circuit 6

will cease to oscillate. In order to prevent the complete cessation of the oscillations and consequent disturbances of the speech, it is advisable to connect in parallel with the condenser 9 an additional resistance 15 which is 55 of such degree that the oscillations in the circuit 6 will not cease when the resistance of the modulating tube 11 is infinitely high.

The above-mentioned arrangement may be used to good advantage also in case the sending arrangement consists of a so-called controlling or steering sender, and the operating sender proper is only a high frequency amplifier. By means of the controlling sender only high frequency grid potential is 60 generated in the well known manner which is then conducted to the grid of the operating sender proper (amplifier). The above described effect of the grid discharge may then be applied either to the tube of the controlling 65 sender or conducted between the grid and the cathode of the operating tube proper (amplifying tube). Obviously the grid conductor of the operating tube (amplifying tube) which leads to the coupling, may be 70 protected against direct current by inserting a condenser. It is immaterial in what manner the grid coupling is accomplished in the case of amplifying or oscillation generating tubes, whether it is accomplished by galvanic, inductive or capacitive means or by 75 means of a grid circuit connection.

Having described my invention, what I claim is:

1. In combination a first electron discharge 85 tube having cathode, anode and control electrodes, an inductance and a condenser connected in series between the cathode and control electrodes the inductance having a terminal connected to the cathode and the capacity having a terminal connected to the control electrode, a second inductance connected between the cathode and anode electrodes and coupled to the first inductance for generation of oscillations, a second electron 90 tube having an anode and a cathode connected in parallel with said series connected inductance and capacity, means for varying the conductivity of said second tube for controlling the potential of the control electrode of 95 100

said first tube and means between said first mentioned control electrode and said second electron tube for protecting said second electron tube from high frequency oscillations 5 generated by said discharge tube.

2. A high frequency transmitting device comprising an electron discharge tube having a cathode, an anode and a control electrode, a controlling circuit for said control electrode comprising two parallel branches one of said branches comprising a thermionic tube acting as a variable resistance and the other of said branches comprising a condenser and a resistance in parallel, and means in said 10 controlling circuit and common to both of said branches for protecting said thermionic tube from high frequency oscillations generated by said discharge tube.

3. In a transmitting device, an electron discharge tube having cathode, anode and control electrodes, an inductance and a condenser connected in series between the cathode and control electrodes the inductance having a terminal connected to the cathode and the 15 capacity having a terminal connected to the control electrode, a resistance circuit in parallel with said inductance and capacity for controlling said control electrode comprising a fixed resistance and a variable resistance in 20 parallel, means for varying said variable resistance in accordance with signals to be transmitted and means controlled by said fixed resistance whereby a maximum value of 25 said resistance circuit may be predetermined.
